UNITED STATES PATENT OFFICE.

JOHN F. JAAP, OF CHICAGO, ILLINOIS, ASSIGNOR TO COOK ELECTRIC COMPANY, OF CHICAGO, ILLINOIS, A CORPORATION OF ILLINOIS.

CABLE-TERMINAL STRUCTURE.

Application filed April 23, 1923. Serial No. 633,942.

This invention relates to cable terminal structures and more particularly to structures for terminating lead-covered aerial cables, such for example as telephone cables.

5 It is a common practice to terminate aerial telephone cables and the like within a suitable terminal box or housing, which may be mounted out-of-doors upon a pole or building. In most instances, the terminal housing 10 is placed on a pole or other structure at a point somewhat below the horizontal portion of the cable line, and furthermore, it is usually desirable to have the cable enter the housing from the under side, which enables 15 the terminal connections to be housed beneath a moisture-proof container or hood, which may be installed and removed as a unit and the upper surface of which is unbroken by the use of water-proof doors or 20 covers. Such practice, however, is open to the possible disadvantage that the stub of the cable connecting the cable terminal with the overhead cable line must be sealed into the terminal housing, then shaped in a 25 curved form and extended upwardly along the pole or other structure and spliced to the main cable by the linemen. During this operation, the bent portion of the cable may be in some instances subjected to the possibility 30 of being distorted or injured by kinking.

A further possible disadvantage with this practice arises from the vibration of the curved stub of cable, which vibration may be 35 transmitted to and also to some extent concentrated at the middle of the curved portion and sometimes will eventually cause crystallization and breaking down of the sheathing at this point. The structure comprising 40 my invention has been found to be especially useful in installations where the above difficulties are likely to be encountered. However, the above statements are not intended to condemn the use of the previously 45 known structures in all instances.

As a result of these possible disadvantages with previous practices, the practice of bringing the cable out of the top of the terminal housing at a point as close to the pole 50 as possible has often been followed. However, if the cable is brought out at the top of the housing, it is necessary to use a housing provided with a water-proof door, giving access to the connections inside, since 55 then it will no longer be possible to remove

the upper part of the housing as a whole because of the cable being sealed therein. The use of housings with moisture-proof doors will often necessitate a much more expensive and less durable construction than the removable hood type having the cable entrance at the under side through the base of the housing. It is also apparent that the metal hood type of structure is much easier to maintain in a water-proof condition. 60

Accordingly, one aim of this invention is to provide an improved structure wherein the cable may be advantageously brought out of the terminal housing from the under side thereof and by the use of which the cable 65 will not be subjected to the possibility of kinking during or after installation.

A further object of my invention resides in the provision of a structure of the above indicated character, in which excessive vibration and its destructive effects at the curved portion of the cable are eliminated. 70

A still further object of my invention is the provision of a device of the character indicated which is easily installed, convenient to use, comparatively inexpensive to manufacture and which is very durable even under adverse service conditions. 75

Further objects and advantages will appear upon reference to the following description and the appended claims, taken together with the accompanying drawing in which—

Figure 1 is a side elevational view illustrating one embodiment of my invention, as 80 installed in operating position.

Fig. 2 is a sectional view taken upon line 2—2 of Fig. 1;

Fig. 3 is a detail view illustrating a modified form of my invention; and

Fig. 4 is a detail view of a nozzle embodied in the structure shown in Fig. 1. 85

Referring to Fig. 1, an aerial lead-covered cable line is represented at 10. A container or hood 11 serves to house the terminal connections of the cable. The hood 11 may rest upon a platform or base member 12, which in turn may be mounted upon a pole or other structure 13, which also in this instance serves to support the cable line. The platform 12 may preferably comprise an integral casting as illustrated, having a bracket portion 14 for attachment to the supporting structure in any suitable and well known manner, as by means of a cross piece 15. 100

The platform 12 may be formed with a 110

perforation 16 at a point beneath a core-box 17 for permitting the passage therethrough of the cable. It is desirable that the cable should be provided with a moisture-proof seal at a point where it passes into the core-box and accordingly, I have provided a nozzle or nipple member 18 into which the cable may be soldered. The nozzle 18 should preferably be of a slightly larger diameter than the cable sheath and may have its lower end beveled inwardly at 19 to provide a shoulder against which suitable packing 20, such as asbestos, may be pressed. In installing the cable within the nozzle 18, the cable sheath should preferably be first scraped clean and then inserted in its final position. The asbestos packing 20 may be securely packed around the cable sheath just outside the nozzle and then may be pressed inwardly against the shoulder at 19. A sleeve of solder 21 may then be inserted and firmly pressed down. When the parts have thus been assembled, sufficient heat may be applied around the outside of the nozzle to cause the solder to melt and seal the cable in position. The nozzle should preferably be provided with an exterior shoulder 22 near its upper end, which will abut the bottom surface of the core-box 17 when the nozzle is inserted through the perforation 16. The upper edge of the nozzle may be beveled or rolled outwardly at 23 in order to firmly fix the nozzle in place within the core-box. The use of a nozzle of this character eliminates the necessity of a skilled cable workman for assembling the device without lowering the quality of the resulting construction.

After extending downwardly from the core-box 17 through the nozzle 18, the cable may be brought over toward the supporting structure 13 by a gradual and uniform bend as indicated at 24, preferably semi-circular in form. The cable may then extend upwardly through a second perforation at 25 in the platform 12 adjacent the supporting structure 13. The perforation 25 may be provided with a nozzle 26 similar in construction and installation to the nozzle 18 which serves to rigidly retain the cable at this point. From the nozzle 26 the cable may extend upwardly along the structure 13 to the horizontal portion of the cable line.

With a construction of the above described character, the hood 11 may be fabricated of light sheet metal and may be installed upon or removed from the base 12 as a unitary structure in the form of a cap. Such a hood in no way interferes with the entering cable terminal and connections and when removed renders the core-box 17 and the terminal connections easily accessible from all sides. The use of water-proof doors or hand openings and their accompanying disadvantages are thus avoided.

It is also apparent that the more common

disadvantages of this class of terminal structures having cable entrances through their base members are here eliminated. In accordance with this invention, the cable is securely fixed and supported at the nozzle 26 so that while the lineman is carrying the cable upwardly along the structure 13 and forming a splice with the horizontal line portion 10, there will be practically no opportunity for the curved portion 24 to become kinked or distorted. Furthermore, any vibrations which may be transmitted along the cable line or through the mounting structure 13 will have a tendency to vibrate the platform 12 and the attached curved portion of the cable at 24 only as a unitary structure, if at all.

The curved portion 24 being fixed at both ends to the rigid platform and core-box structure it is subject to substantially no relative vibration in respect to its points of support and consequently, the danger of crystallization and breaking of the sheath as a result of vibrations is eliminated. Terminals constructed and assembled in the above described manner have given satisfactory service for long periods of time at locations and under conditions that have proven destructive to cable terminals as commonly arranged.

In the modification illustrated in Fig. 3, the entire curved portion of the cable is shown enclosed by a section of pipe 27, which at its ends 28 and 29 fulfills the functions of the nozzles 18 and 26, above described. This construction serves to fully support the entire curved portion of the cable and thereby prevents all appreciable relative vibration between its various parts and its fixed points of support at 28 and 29. Furthermore, the platform together with the short length of pipe 27 and the core-box 17 may be assembled, if desired, as a part of the manufacturing process and before being carried up and attached to the structure 13. The curved portion being completely housed and protected by the pipe is not subject to mechanical injury from kinks, undue bending or other causes. The cable may be sealed into the end 29 of the pipe with any suitable known filling compound.

While I have shown and described several embodiments of my invention, I wish it to be understood that I do not desire to limit myself to the specific construction herein shown, since various changes and modifications may be made without departing from the spirit and scope of the following claims.

Having thus described my invention, what I claim as new and desire to secure by Letters Patent of the United States, is:

1. A cable terminal structure comprising a platform, a terminal housing thereon, a cable extending downwardly through said platform at a point to one side of said hous-

ing and thence upwardly to a point beneath said housing and through said platform into said housing, and means sealed at the cable at each of said points for rigidly fixing said cable against vibration in respect to said platform.

2. A cable terminal structure comprising a platform, a terminal housing thereon, a cable provided with a sheath and extending 10 downwardly through said platform at a point to one side of said housing and thence upwardly to a point beneath said housing and through said platform into said housing, and means fixed in respect to said platform for enclosing the portion of said cable sheath beneath the platform for preventing 15 kinking and vibration of said portion.

3. A cable terminal structure comprising a platform, a terminal housing thereon, a 20 multi-wire cable having a metallic sheath and extending downwardly through said platform and thence curved upwardly and again extending through said platform to said housing, and a section of pipe rigidly 25 fixed at both ends in relation to said platform and embracing the portion of said cable beneath the platform for preventing kinking and vibration of said portion.

4. As an article of manufacture, a cable 30 terminal structure comprising a terminal housing platform, said platform being provided with a pair of spaced perforations, and a section of pipe for enclosing and restraining from vibration a portion of cable, 35 said pipe being positioned beneath said platform and having its ends curved upwardly

and extending through and rigidly fixed within said perforations.

5. As an article of manufacture for use with a terminal housing having a cable entrance from the under side, a cable terminal structure comprising a terminal housing platform, said platform being formed with a pair of spaced perforations, one of said perforations being adjacent the point of support of said platform and the other of said perforations being beneath the terminal housing position, and means extending between said perforations for embracing and sealing a portion of a cable in fixed position 50 therein.

6. In a device of the type described for use with a terminal housing having a cable entrance from the under side, a cable terminal structure comprising a terminal housing platform, a cable provided with a sheath and extending downwardly through said platform at a point adjacent the point of support of said platform and thence curved 55 upwardly and extending through the platform into the housing, and means comprising a section of pipe enclosing the portion of said cable sheath beneath the platform for preventing kinking and vibration of said portion, said section of pipe having an end 60 rigidly fixed to said platform adjacent to the terminal housing and having its other end sealed to the cable and fixed adjacent the point of support of said platform.

In witness whereof, I have hereunto subscribed my name.

JOHN F. JAAP.
